UNITED STATES PATENT OFFICE.

MOSES H. EISEMAN, OF CHICAGO, ILLINOIS, ASSIGNOR OF ONE-HALF TO
WORMS & LOEB, OF CHICAGO, ILLINOIS, A FIRM.

DESIGN FOR A BELT.

SPECIFICATION forming part of Design No. 36,164, dated December 9, 1902.

Application filed September 11, 1902. Serial No. 123,038. Term of patent 3½ years.

To all whom it may concern:

Be it known that I, MOSES H. EISEMAN, a citizen of the United States, and a resident of Chicago, in the county of Cook and State of Illinois, have invented and produced a new, original, and ornamental Design for Belts, of which the following is a specification, reference being had to the accompanying drawing, forming a part thereof.

10 The figure is a view in elevation, showing the belt in extended position.

As shown, the belt comprises two strips or sections A and A' of open-work fabric. Between the borders *a* and *a'* of each strip A and A' extend the narrow bands or ribbons *a*², that are run through the meshes or loops *a*³ of the strip. At the back of the belt are three loops or rings B, B', and B², the loops or rings B and B' being surmounted by the 20 loop or ring B², that is secured to the loops or rings B and B'. Each of these loops or rings is of quadrilateral shape and is covered with cords *b*, that extend radially across the bars forming the rings or loops, the edges of 25 each of the rings or loops being bounded by a cord *b*³. One of the strips or sections A

passes through the two rings B and B', while the other one of the strips or sections A' passes through the ring B². At each side of the belt and at a distance from the rings or loops B, 30 B', and B² is a ring or loop B³, similar in appearance to the rings or loops B, B', and B², and through each of these loops B³ the sections A and A' of the belt pass. At the front of the belt are two rings or loops B⁴ and B⁵, 35 similar in appearance to the loops B, B', and B². The strips or sections A and A' pass through the loop B⁴ and through the loop B⁵. To the loop B⁴ is secured an eye, and to the ends of the sections A and A' adjacent the loop B' is 40 secured a hook to engage said eye when the belt is clasped about the person of the wearer.

Having thus described my invention, what I claim as new, and desire to secure by Letters Patent, is—

45 The ornamental design for a belt as herein shown and described.

MOSES H. EISEMAN.
